UNITED STATES PATENT OFFICE.

THOMAS E. BARROW, OF MANSFIELD, OHIO.

CUFF-FASTENER.

SPECIFICATION forming part of Letters Patent No. 372,887, dated November 8, 1887.

Application filed April 1, 1887. Serial No. 233,270. (No model.)

To all whom it may concern:

Be it known that I, THOMAS E. BARROW, a citizen of the United States, residing at Mansfield, in the county of Richland and State of Ohio, have invented certain new and useful Improvements in Cuff-Fasteners; and I do declare the following to be a full, clear, and exact description of the invention, such as will enable others skilled in the art to which it applies to make and use the same.

My invention relates to that class of cuff-fasteners which, by means of a series of communicating openings, are adapted to be engaged with and adjusted upon the ordinary stud or button of the wristband. It is the object of my present invention to provide a means for the attachment of the cuff to such a fastener at a point intermediate between the ends of the latter, preferably at about its middle. I am thus enabled to secure a more advantageous capability of adjustment of the cuff upon the wristband, the cuff being adapted by my device to be attached to the wrist by its rear button-holes, with said button-holes either in front of or in rear of the stud of the wristband.

In order to enable my invention to be more clearly understood, I have shown in the accompanying drawings a means for carrying the same into effect.

In said drawings, Figure 1 is a perspective view of a cuff-fastener embodying my invention. Fig. 2 is a sectional view of a cuff and wristband, showing the application of my fastener thereto. Figs. 3 and 4 are perspective views of other forms of fasteners, also embodying my invention.

My invention consists, essentially, in the combination, with the two proximate spring side pieces, F, so shaped as to form between them the series of openings G, of a means for attaching the cuff at or near its rear end (preferably by its rear button-holes, i,) to said side pieces at a point intermediate between their ends, so that one or more of said openings G shall be at each side of said means of connection.

In applying the spring side pieces to the stud or button of the wristband the shank of the latter is passed between the pieces, the latter yielding as the shank passes from one opening

to the other, while the head of the stud or button rests upon the upper face of the spring side pieces.

While the means of attachment of the rear end of the cuff to these spring-pieces may be varied to a considerable extent, it must, nevertheless, be of such character as not to interfere with this adjustment of the spring-pieces forward or backward upon the wristband-stud. One of the simplest devices for this purpose is a bar, f, secured to the spring-pieces F, rising above them to a sufficient height to leave room for the passage of the wristband-stud between the spring-pieces and said bar, 65 and carrying any suitable means for engaging and holding the cuff.

In Fig. 1 the bar runs longitudinally and substantially parallel with the side pieces, being attached thereto at its ends. This arrangement gives strength and stability to the whole fastener, while at the same time it allows of the free spring action of the side pieces. In said figure the means f', carried by the bar for engagement with the cuff, consists 75 of a button or stud adapted to be inserted through one or both of the rear button-holes, i.

In Fig. 3 the bar f is secured to the side pieces, F, at one end only, and extends for about one-half their length. In this construction, however, there is a liability that the bar may be caught and bent out of its proper position. In this latter figure the means for connection with the cuff consists of a hook adapted to engage with the button-holes of the cuff. 85

In Fig. 4 the bar f runs from end to end of the side pieces, and is attached thereto at both ends, as in Fig. 1. In this latter figure, however, the means for the attachment of the fastener to the cuff consists of a bent portion of the bar f, so formed as to have the substantial functions of a stud or hook in entering the button-holes of the cuff and retaining the latter in place upon the fastener.

The bar f might be connected with the main portion of the fastener at substantially the middle of the spring-bars and pass outward laterally and upward, so as to leave room for the passage of the head of the wristband-stud, without departing from my invention, which, 100 as already stated, may be embodied in other forms not necessary to be here further de-

scribed or illustrated, the description and illustration already given being sufficient for a clear understanding of the invention.

Having thus described my invention, what 5 I claim, and desire to secure by Letters Patent of the United States, is—

1. In a cuff-fastener, the combination, with a main portion having a series of spring-operating openings or eyes, of a bar, *f*, connected to with and carried by said portion and having, intermediate between the ends of said portion, means, substantially as described, as the part *f'*, for engagement with the cuff, as set forth.

2. In a cuff-fastener, the combination, with 15 the main portion having a series of spring-operating openings or eyes, of a bar, *f*, parallel with and above said portion and secured thereto

at each end, said bar being provided with means, substantially as described, as the part *f'*, for engagement with the cuff, as set forth. 20

3. In a cuff-fastener, the combination, with the main portion provided with a series of spring-operating openings or eyes, of a bar, *f*, extending parallel with and at a distance above said portion and secured thereto at each end, 25 said bar being bent in the middle to form a hook for the engagement with the cuff, as set forth.

In testimony whereof I affix my signature in the presence of two witnesses.

THOMAS E. BARROW.
